UNITED STATES PATENT OFFICE.

ANTON A. BAKKE, OF FENTON, IOWA.

FOLDING CRATE.

SPECIFICATION forming part of Letters Patent No. 780,471, dated January 17, 1905.

Application filed June 10, 1904. Serial No. 212,011.

To all whom it may concern:

Be it known that I, ANTON A. BAKKE, a citizen of the United States, residing at Fenton, in the county of Kossuth, State of Iowa, have invented certain new and useful Improvements in Folding Crates; and I do hereby declare the following to be a full, clear, and exact description of the invention, such as will enable others skilled in the art to which it appertains to make and use the same.

This invention relates to crates, and more particularly to those designed for use in shipping eggs and similar articles, and has for its object to provide a crate which when empty may be folded into small compass and which may be quickly unfolded when desired.

A further object is to provide a construction in which the crate will be prevented from accidentally collapsing when unfolded, another object being to provide a crate which may be simply and cheaply constructed.

A still further object is to provide a crate which will be thoroughly braced and which will be so constructed that the several portions thereof will not be readily disconnected through hard usage.

Other objects and advantages will be apparent from the following description, and it will be understood that modifications of the specific construction shown and described may be made, and any suitable materials may be used without departing from the spirit of the invention.

In the drawings forming a portion of this specification, and in which like numerals of reference indicate similar parts in the several views, Figure 1 is a side elevation of the crate. Fig. 2 is an end view. Fig. 3 is a longitudinal section on line 3-3 of Fig. 2. Fig. 4 is a top plan view of the crate with the cover removed. Fig. 5 is a longitudinal section of the crate folded. Fig. 6 is a detail view showing the manner of hinging the partition to the bottom of the crate.

Referring now to the drawings, the present invention comprises a bottom portion 6, including side walls 7 and 8 and end walls 9 and 10 and having longitudinally-extending semi-cylindrical braces 11 secured to the under face of its bottom 12, adjacent to the edges thereof

and extending from end to end of the crate. The bottom portion 6 is formed of a single piece of metal, the side and end walls being bent upwardly at right angles to the bottom, as shown, the end walls having corner-flaps 13, 55 which are soldered or otherwise secured to the outer faces of the side walls.

Hinged to the side walls 7 and 8 are supplemental walls 14, which are movable to lie in a plane with their respective side walls or 60 to extend inwardly therefrom and to lie one upon another, as shown in Fig. 5.

Secured to the upper face of the bottom 12, adjacent to the ends thereof, are pairs of hinges 15 and 16, which are also secured to 65 end pieces 17 and 18, which are movable upon the hinges to lie against the upper face of the bottom 12 or to extend upwardly therefrom and to lie against the inner faces of the end walls 9 and 10 of the bottom portion, in which 70 position they extend upwardly thereabove and lie with their outer end edges flush with the free side edges of the supplemental walls 14 when the latter are in their first-named position. The ends of the supplemental 75 walls 14 are turned inwardly at right angles, as indicated by the numeral 19, and when the parts are in the position just described these angular portions lie against the outer faces of the end pieces 17 and 18, the walls 14 being 80 also provided with angular plates 20 adjacent to their ends, the portions 21 of the plates extending at right angles to the supplemental walls and lying against the inner faces of the end pieces 17 and 18.

Formed through the bottom 12 of the bottom portion, adjacent to either side thereof, is a pair of perforations 22, one perforation of each pair being disposed at either side of the central transverse axis of the bottom, and 90 formed through the braces 11 are perforations 11', which align with the pairs of perforations 22 for the reception of the spaced legs 23 of staples 24, the bights 25 of which extend above the upper face of the bottom and are engaged in 95 perforations 26 adjacent to the lower edge of a transverse central partition 27, which is thus movable upon the staples to extend at right angles from the bottom or to lie thereagainst.

Secured transversely of the side walls 14 100

are spaced members 28 and 29, which are disposed to receive the edges of the partition 27 therebetween when the latter is in upright position, these spaced members 28 and 29 being formed from a single piece of metal which is bent transversely into U shape. Through the spaced members 28 and 29 are formed perforations 30 and 31, which aline with each other, as shown, and formed through the central partition 27 are perforations 27', which aline with the perforations 30 and 31 when the edges of the partition are engaged between the spaced members 28 and 29, these alining perforations being arranged for the reception of pins 32 to hold the several parts in position when the crate is unfolded.

Secured to the outer faces of the end pieces 17 and 18 are cleats 33, which serve as handles by which the crate may be carried, and secured between the cleats and the end pieces are the lower ends of spring-tongues 34, which extend upwardly and have their free end portions turned outwardly, as shown, the end pieces 17 and 18 being provided with openings 35 therein arranged for the movement of the upper portions of the tongues therethrough to bring the ends of the outwardly-turned portions flush with the outer faces of the end pieces.

30 A cover 36 is provided having depending side and end walls 37 and 38, which are arranged to lie against the outer faces of the supplemental walls 14 and the end pieces 17 and 18, respectively, when the cover is in operative position, the depending end walls 38 being provided with longitudinal slots 39 for engagement by the outwardly-turned portions of the spring-tongues 34 to hold the cover in position, though it will be understood that 40 the tongues may be moved as mentioned above to disengage their outwardly-turned portions from the slots.

In folding the crate the pins 32 are disengaged from the alining perforations 30, 31, and 27', and the supplemental walls are moved outwardly to disengage the spaced members from the partition 27 when the latter is moved to lie against the upper face of the bottom 12. The outward movement of the supplemental walls also disengages the angular end portions 29 and the angular portions 21 of the plates 20 from the end pieces, thus permitting movement of the end pieces upon their hinges to lie upon the upper face of the bottom, after 50 which the supplemental walls are folded inwardly to lie one upon another, as shown, and the top 36 is engaged with the walls of the bottom portion, the end walls 38 of the cover having hasps 40 thereon for engagement with 55 staples 41, carried by the end walls of the bottom portion to hold the cover upon the bottom portion, it being understood that suitable locks are engaged with the staples.

The hinges 15 and 16 are secured to the bottom 12 by means of bolts 16', which are passed through perforations in the bottom and alining perforations in the braces 11, so that these bolts, together with the legs 23 of the staple 24, hold the braces in position, it being understood that the ends of the legs 23 are headed over against the outer faces of the braces. 65 70

What is claimed is—

1. A folding crate comprising a bottom, upwardly-extending side and end walls secured thereto, supplemental walls hinged to the upper edges of the side walls for movement to form continuations thereof, or to lie at right angles thereto above the bottom, braces disposed against the under face of the bottom, hinges disposed with one leaf upon the bottom, 80 bolts passed through said leaves, the bottom and braces to hold the hinges and braces in position, end pieces secured to the remaining leaves of the hinges and arranged for movement to lie against the bottom or to extend 85 upwardly therefrom and against the end walls, a partition hinged to the bottom between the ends thereof, and plates bent to form spaced members, and connecting-webs disposed transversely of the supplemental walls with their 90 webs thereagainst, said plates being disposed for the reception of the edges of the end pieces and the partition between their spaced portions.

2. A folding crate comprising a bottom having 95 braces disposed against its under face, side walls connected with the bottom for movement to extend upwardly therefrom, or to lie parallel therewith, perforations formed through the bottom and through the braces, hinges disposed with one leaf upon the bottom and having openings through said leaves and in alinement with the perforations, bolts engaged with the alining perforations and openings, end pieces secured to the remaining leaves of 100 the hinges and arranged for movement to lie against the bottom or to extend upwardly therefrom, alining perforations formed through the bottom and braces between the ends thereof, staples engaged in the perforations and having the free ends of the legs secured against the outer faces of the braces, the bights extending above the bottom, a partition having perforations therethrough with 105 which the bights of the staples are engaged, 110 said partition being arranged for movement to extend upwardly from the bottom, or to lie thereagainst, means for holding the several portions in their upwardly-extending positions, and a closure for the crate. 115 120

In testimony whereof I affix my signature in presence of two witnesses.

ANTON A. BAKKE.
